(57) **CLAIM**

The ornamental design for a sidecutter, as shown and described.

DESCRIPTION

FIG. 1 is an outside surface view of a sidecutter showing our new design;

FIG. 2 is a top view thereof;

FIG. 3 is an inside surface view thereof;

FIG. 4 is a bottom view thereof taken in the direction of the arrows 4—4 on FIG. 3;

FIG. 5 is a front view thereof;

FIG. 6 is a rear view thereof;

FIG. 7 is an outside perspective view thereof; and,

FIG. 8 is an inside perspective view thereof.

All broken lines shown on the surfaces of FIGS. 2, 3, 4, and 8 are for illustrative purposes only and form no part of the claimed design.
